UNITED STATES PATENT OFFICE.

PARKE W. PEARSON, OF BLOOMINGDALE, INDIANA.

BUCKLE.

1,209,017.

Specification of Letters Patent. Patented Dec. 19, 1916.

Application filed November 20, 1915. Serial No. 62,567.

To all whom it may concern:

Be it known that I, PARKE W. PEARSON, a citizen of the United States, residing at Bloomingdale, in the county of Parke and 5 State of Indiana, have invented certain new and useful Improvements in Buckles, of which the following is a specification.

The invention relates generally to an improvement in buckles, and particularly to 10 belt buckles with which a belt is designed to be so connected as to permit size variation adjustment at the pleasure of the wearer.

The present improvement resides in the 15 provision of means whereby the belt, after coöperative connection with the buckle, may be permitted an easy and convenient adjustment and readily secured in such adjusted position against accidental disarrangement, the construction permitting the 20 complete operation without the necessity of removing the belt from the person.

The specific means employed contemplates the use of a tongue, integral with and 25 projecting from one end of the buckle proper, so that the tongue will lie between the return fold sections of the belt or the like, combined with a clamping sleeve to slidably 30 embrace the belt sections, and when desired surround the belt sections and tongue, with the effect to clamp said sections tightly 35 onto the tongue and prevent movement of the belt sections, to thus maintain the adjustment.

The invention, in the preferred embodiment of details will be described in the following specification, reference being had to the accompanying drawings, in which:—

Figure 1 is a perspective view illustrating 40 the invention, the belt being broken away. Fig. 2 is a perspective view of the buckle. Fig. 3 is a longitudinal central sectional view to illustrate the clamping cooperation of the parts. Fig. 4 is a perspective view of the clamping sleeve.

In the following description it is to be understood that, notwithstanding the illustration of the improvement as applied to a belt buckle, the invention is applicable to 50 all types of buckles and other devices to which a flexible connector is adapted for adjustment, and to be held in such adjustment; and that, to this end, the term

“buckle” herein is intended to cover any and all such structures.

In the specific embodiment of the invention illustrated, 1 represents a buckle, formed near one end with a belt-receiving slot 2, and at the opposite end with any type of connector 3, for coöperation with a 55 similar device 4, carried by the free end of the belt 5. In the type shown, one end of the belt is passed through the slot 2, returned upon itself, and its free end connected by a slip-loop 6 to the main length of 60 belt, so that by slidably adjusting the return portion of the belt in an obvious manner, the length of the belt proper may be 65 varied as desired.

The above-described parts are usual, and 70 the present invention contemplates the addition thereto of means whereby the belt return portions may be in effect locked against independent movement after such adjustment, to thereby maintain the adjusted 75 length of the belt against possible variation during use, the locking means being, however, readily operable to permit additional belt adjustment when desired. The locking 80 means includes a tongue 7, projecting longitudinally from and in the plane of the buckle proper, such tongue being arranged adjacent the slot 2 and being of effective length beyond the buckle. The tongue is 85 rigid with the buckle, preferably of a thickness equal to the thickness of the buckle, and of a width corresponding to the width of the belt. A locking sleeve 8 is arranged to co-operate with the tongue, said sleeve being 90 preferably an open-ended rectangular structure, of sufficiently rigid metal, and having an interior dimension corresponding to the combined transverse sectional dimensions of the tongue and return portions of the belt.

In use the locking sleeve or slide, when 95 adjusting the belt, occupies a position about the return sections of the belt beyond the tongue 7, and the said return belt sections may then be freely adjusted to vary the length of the belt. The return belt sections 100 overlie and underlie the tongue 7, and after adjustment to the desired size, the tongue is utilized as a base for a clamping action, by forcing the sleeve to and over the tongue and adjacent portions of the belt sections. 105 The belt sections are thus clamped against

the tongue and held in such position by the sleeve, accidental displacement being impossible. This is further gained by the fact that to move the belt sections they would 5 have to travel in opposite directions, and hence move the sleeve in both directions, which, of course, is impossible.

The operation of the sleeve 8 is all that is necessary in locking the belt in adjusted position or releasing it to permit further adjustment, hence it is obvious that either complete operation may be readily performed while the belt is about the person of the wearer, thereby providing for a completely accurate and comfortable fit of the belt, and avoiding the several trials and adjustments of the belt necessary to a fit under other circumstances.

The invention is applicable to suspender buckles, and the like, and the improved buckle is of course to be made in any de-

sired size, of any appropriate material, and of any specific type, as may be best adapted for the particular use intended.

What is claimed, is:—

A belt buckle formed with a strap receiving opening and having an integral tongue projected beyond the buckle proper to be interposed between the strap sections beyond the opening, and a loop member to embrace 30 the said strap sections and tongue to bind the strap sections with relation to the tongue, and serve as a means for preventing sliding movement of the strap in the opening.

In testimony whereof, I affix my signature in presence of two witnesses.

PARKE W. PEARSON.
